UNITED STATES PATENT OFFICE.

JOHN R. SINGER, OF ELWOOD, AND JOHN F. BRICE, OF BLUFFTON, INDIANA; SAID SINGER ASSIGNOR TO SAID BRICE.

WRENCH.

Application filed August 11, 1923. Serial No. 656,767.

To all whom it may concern:

Be it known that we, JOHN R. SINGER and JOHN FRANK BRICE, citizens of the United States, residing at Elwood and Bluffton, respectively, in the counties of Madison and Wells, respectively, and State of Indiana, have invented certain new and useful Improvements in Wrenches, of which the following is a specification.

10 This invention relates to an improved wrench and seeks, among other objects, to provide a device of this character which may be quickly adjusted.

The invention seeks as a further object, to 15 provide a wrench wherein after the wrench jaws have been engaged with the work, the movable jaw of the wrench may be shifted to clamp the work.

And the invention seeks, as a still further 20 object, to provide a wrench characterized by structural simplicity and which may thus be manufactured and sold at moderate cost.

Other and incidental objects will appear 25 hereinafter.

In the drawings:

Figure 1 is a side elevation of our improved wrench, parts being broken away and illustrated in section,

30 Figure 2 is a view looking at the rear edge of the wrench, and

Figure 3 is a transverse sectional view on the line 3—3 of Figure 1, looking in the direction of the arrows.

35 In carrying the invention into effect, we employ a shank 10 rectangular in cross section, and formed on the shank at one end thereof is a fixed jaw 11, the shank providing a handle at its opposite end portion.

40 Slidable upon the shank to coact with the fixed jaw is a movable jaw 12 and arranged in the rear of the jaw 12, is a block 13. This block is also slidably fitted upon the shank, and screwed or otherwise detachably secured at one end in the shank receiving aperture of the jaw 12 to overlie the rear edge of the shank is a metal connecting strap 14 extending freely through the shank receiving opening in the block 13 and provided with an outwardly turned stop lug 15.

45 Formed in the block 13 from the forward end thereof is a recess 16 and communicating with said recess is a reduced cylindrical bore 16', there being a slot 17 extending 50 from the inner end of the recess and open-

ing through the outer side of said block. Formed on the shank 10 at its forward edge is a rack 18, and disposed within the recess 16 is a locking pin or plunger 19 slidably fitting through the bore 16' to cooperate with the rack. The pin or plunger is formed near the outer end thereof with an annular flange or shoulder 20 slidably fitting the recess 16, and bearing against said flange is a spring 21 retained within the recess by 55 a plug 22 threaded into the recess at its outer end. Thus, the spring will function to urge the plunger into engagement with the rack, and pivoted in the slot 17 of the block is a lever 23 cooperating at its inner end 60 with the flange 20 so that the lever may be rocked for retracting the pin or plunger. Connecting the jaw 12 with the block 13 at the forward side of the shank is a right and left threaded adjusting screw 24 provided midway between its ends with a preferably milled thumb disc 25.

As will now be seen in view of the foregoing, the wrench shank may be grasped when, by rocking the lever 23 to retract the 65 pin or plunger 19, the jaw 12 and block 13 may be shifted as a unit along the shank to advance the jaw toward the fixed jaw 11 to engage the work. Upon the release of the lever 23, the movable jaw will then be locked in adjusted position when the adjusting screw 24 may be rotated for clamping the work between the jaws. Slipping of the wrench may thus be prevented while, as will 70 be seen, adjustment of the wrench may be 75 easily and quickly effected. In Figure 1 of the drawings, the screw 24 is shown as having been turned to shift the jaw 12 and block 13 toward each other to the limit of 80

their movement in such direction and, as 85 will be noted, the adjusting screw may be counter-rotated for shifting the movable jaw a considerable distance in the opposite direction. However, to prevent disengagement of the screw from the jaw 12 and 90 block 13, when the screw is thus turned, we provide the connecting strap, the lug 15 of which is disposed to abut the flat face or abutment 22' of the block for limiting the 95 jaw and block in their separating movement before the adjusting screw becomes released therefrom. Complete separation of the jaw and block will thus be prevented and accidental loss of the adjusting screw 100 obviated.

Having thus described the invention, what is claimed as new is:

A wrench including a shank having a fixed jaw, a movable jaw carried by the shank to cooperate with the fixed jaw, a block adjustable upon the shank, said block having a recess extending at right angles to the shank and a reduced cylindrical bore communicating with the recess, there being 10 a slot formed in the block and extending from the inner end of the recess through the edge of the block, a pin mounted in the cylindrical bore and adapted to engage the shank and lock the block thereto, an annular flange formed on the pin and fitting within the recess, a removable plug closing the outer end of the recess, a spring housed 15 within the recess between the plug and the

flange on the pin, a lever pivoted in and projecting from the slot and having its 20 inner end bearing against the inner face of the flange, means coacting between the block and movable jaw for adjusting the movable jaw with respect to the fixed jaw, and a connecting strap secured to one end of the 25 movable jaw and extending through the block and provided at its free end with an outwardly turned lug adapted to bear against the adjacent face of the block for limiting the movable jaw and said block in 30 their separating movement.

In testimony whereof we affix our signatures.

JOHN R. SINGER. [L. s.]
JOHN F. BRICE. [L. s.]
